UNITED STATES PATENT OFFICE.

CHARLES H. PLACE, OF MAMARONECK, NEW YORK, ASSIGNOR TO NEW YORK
MACKINTOSH CLOTHING COMPANY, OF NEW YORK, N. Y., A CORPORATION
OF NEW YORK.

DESIGN FOR A WATER-BAG.

47,827.

Specification for Design.

Patented Sept. 14, 1915.

Application filed March 16, 1915. Serial No. 14,813. Term of patent 7 years.

To all whom it may concern:

Be it known that I, CHARLES H. PLACE, a citizen of the United States, residing at the village of Mamaroneck, in the county of Westchester and State of New York, have invented a new, original, and ornamental Design for Water-Bags, of which the following is a specification, reference being had to the accompanying drawing, forming part thereof.

I claim:

The ornamental design for a water bag, as shown.

CHARLES H. PLACE.
